(57) **CLAIM**

The ornamental design for a head for portafilter as shown and described.

DESCRIPTION

FIG. 1 is a front, right and top perspective view of a head for portafilter in an unassembled state, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a perspective view showing the head for portafilter in an assembled state.

The broken lines and unshaded areas of the portafilter head in the drawings depict portions of the head for portafilter that form no part of the claimed design.
